UNITED STATES PATENT OFFICE.

ARTHUR R. MILLER, OF CLEVELAND, OHIO, ASSIGNOR, BY MESNE ASSIGNMENTS, TO NATIONAL CARBON COMPANY, INC., A CORPORATION OF NEW YORK.

BRUSH CONNECTION.

1,282,101.

Specification of Letters Patent. Patented Oct. 22, 1918.

Application filed December 14, 1916. Serial No. 136,842.

To all whom it may concern:

Be it known that I, ARTHUR ROSS MILLER, a citizen of the United States, residing at Cleveland, in the county of Cuyahoga and State of Ohio, have invented a certain new and useful Improvement in Brush Connections, of which the following is a full, clear, and exact description.

This invention relates to connections for brushes for dynamo electric machines, contacts for electric switches and similar apparatus. Brushes for motors and generators, as well as certain contacts for electric switches, are usually made of carbon or graphite, and in nearly all cases a flexible conductor is secured directly to the carbon block in order to give a low resistance contact.

In some respects my invention may be considered to be an improvement on the patent granted to Naydor, February 15, 1916, No. 1,171,630; but it is also applicable to other processes of securing flexible conductors or "pigtailed" to brushes.

Referring to the drawings:

Figure 1 is a perspective view of a brush having holes and recesses for receiving the pigtail connection.

Fig. 2 is a perspective view of the slotted copper cup adapted to surround the pigtail inside of a recess in the brush.

Fig. 3 shows the brush after the pigtail has been tamped in position.

Fig. 4 illustrates the brush after the thin copper cup has been bent over the tamped strands of the pigtail.

Fig. 5 illustrates the finished brush.

To apply my improved form of connection, a hole 1 is bored partially through brush 2 and a smaller hole 3 is drilled to intersect the first hole or recess 1. A thin slotted copper cup 4 is then placed in the hole 1, with the slot 5 in line with hole 3. The pigtail is next pushed through the hole 3 and slot 5 and thence out through the protruding cup. The protruding strands of the pigtail are separated and then tamped or compacted into the cup after which it may

be spun as described and claimed in the aforesaid patent to Naydor, if desired. 50

After tamping the pigtail in position, as shown in Fig. 3, the thin copper cup 4 is bent over the tamped strands of the pigtail as shown in Fig. 4, and thoroughly compacted against the strands. Preferably the bent 55 over portion is spun with a suitable tool until a smooth surface is obtained as illustrated in Fig. 5.

While it is preferable to slot the copper cup, a hole would serve the purpose. 60

Brushes having pigtail connections made in this way have a very low resistance, are mechanically strong, and are not injured by heat, as is the case with soldered connections particularly. 65

The copper cup may be made of various thicknesses, but I prefer to make it of #36 B. & S. sheet copper which is substantially .005" in thickness. Preferably the cup is drawn or stamped into the shape illustrated 70 in Fig. 1, although it would be possible to use a short cylinder cut from a thin walled copper tube either without a bottom or with the sides bent over to form a bottom portion.

The pigtailed may be made of strands of 75 any desired thickness, but I prefer to use strands of about #36 B. & S. gage, as the pigtail is then very readily tamped into place.

Having described my invention, what I 80 claim is:

1. The method of attaching a stranded conductor to a brush, which consists in placing a thin metallic cylinder in a recess in the brush, compacting the strands of the conductor solidly into said cylinder, bending over the protruding portion of the cylinder and compacting it solidly against the strands. 85

2. The method of attaching a stranded conductor to a brush, which consists in drilling two intersecting holes into the same, one being larger than the other, to form a seat for the end of the conductor, inserting a thin slotted metallic cup in the said larger 90 hole, passing a stranded conductor through 95

both of said holes, wadding one end of it in the larger hole, bending over the protruding end of said cup and spinning the cup and wadded portion of the pigtail into a compact mass within the brush.

3. A brush having a recess therein, a thin metallic cup in said recess, a pigtail com-

pacted within said cup, the end of the cup being bent over against the portion of the pigtail and compacted thereagainst. 10

In testimony whereof, I hereunto affix my signature.

A. R. MILLER.
